HIGH SPEED CYLINDER PRINTING PRESS

Walther Koeniger, Heidenau, Germany

Application July 10, 1937, Serial No. 153,613
In Germany March 23, 1936

3 Claims.

(CL. 271—3)

This invention relates to high speed cylinder presses for sheet printing.

Its object is to overcome objectionable space consuming requirements for the paper to be fed and for the paper which has been printed. Its further object is to overcome the objection attendant upon the feeding of paper by pushing it to the cylinder, since such pushing compresses the paper upon itself to a certain extent, which consolidation of the fibers is released when the pressure has been removed. As such pressure is removed after the paper has been fed, the resilient expansion of the paper during printing detrimentally affects the registering.

A further object is to provide a simple means to avoid crowding the press by starched paper either to be fed or already printed.

The invention consists in providing stacks for the paper to be printed and for the paper printed at such places in respect to the press cylinder where they are not in the path of the operator of the press, and the invention consists in bringing to the cylinder a paper sheet in its best condition for pointing and registration, the moved means comprising in feeding and delivering the sheet by pulling instead of pushing the sheet.

The invention consists further in mechanism hereinafter to be more fully described with embodiments of the invention shown in the drawings. The invention will be finally pointed out in the claims.

In the accompanying drawings:

Figure 1 is a plan view of a cylinder press embodying the invention, with the parts in their initial position;

Figure 2 is also a plan view of the same with the parts in their end position;

Figure 3 is a front view thereof;

Figure 4 is a plan view of an alternative form, and

Figure 5 is a plan view of another alternative form.

Similar characters of reference indicate corresponding parts throughout the several views.

Referring to the drawings, and more particularly to Figures 1 to 3, the usual cylinder 10 is operated by means well known, and is provided with known guide means 11. At the rear of cylinder 10 are two stacks of paper, the stack 12 being the paper to be fed to the cylinder, and the stack 13 being the paper which has been pointed.

A vertical shaft 19 is supported on the frame 28 of the machine, and upon this shaft 19 is pivotally supported a lever 18 which is provided with some form of suction device of known character, or with some fastening means equally known which grips the front edge of the top sheet of the paper stack. Upon the rotary movement of the lever 18, by suitable known means, it is moved from its initial position as shown in Figure 1, to

its final position as shown in Figure 2. By such movement, the paper sheet is drawn along or pulled, and not pushed, until it is delivered to the cylinder, at which time, when the lever 18 abuts against the guides or against some suitably spaced abutment, the sheet is released and it simultaneously abuts against the usual guides and is positioned for printing. This having been accomplished, the operation is repeated for each sheet to be printed.

In the embodiment shown in Figures 1 and 2, after the printing has taken place upon the sheet, it is gripped by a suction device or other fastening, acting upon the forward end of the paper, and the sheet is pulled away from the cylinder 15 and moved to the printed stack 13. The suction or other device is a lever 20 which is integral with the lever 18, and is moved when the lever 18 is moved. It will be noted that the levers move around the pivot shaft 19, so the sheets 20 partake of a circular path during feeding and during delivery. It will also be noted that in both feeding and delivering, the paper sheet moves with the front end forward. It will be noted, furthermore, that the stacks of paper are out of the path of the operator.

A similar arrangement of the paper stacks is shown in Figure 4. A similar curved or circular path of the paper takes place, and also the paper is gripped at its front edge. Instead of having a two-armed lever, two separate levers are provided. Lever 30 feeds the paper to the cylinder, and a separate lever 31 delivers the paper. Interposed between the two levers is a pinion 32 on a shaft 33 supported on the frame. The lever shafts 34 and 35 have pinions 36 and 37 which engage the pinion 32. The lever shafts are supported on the frame. As is clear, the operation or rotating of the pinion 32, operates or rotates pinions 36 and 37. By such operation, the same actions as described in connection with Figures 1 to 3 takes place.

In Figure 5, one stack 40 is at the front, and one stack 41 is at the rear of the press. A lever 42 feeds the paper to the cylinder from the rear supply stack 41. Another lever 43 delivers the printed paper to the printed stack 40. Each lever 42 and 43 is provided with a segmental gear, 44 and 45, respectively, and these gears are engaged by a rack 46. The movement of the rack 46 by suitable means actuates the levers to feed and deliver, as described.

The arrangements can be made in all sorts of modes so that the sheet can be fed directly to the cylinder by swinging levers; or, if desired, one can put the sheets first on a feeding table whence they are fed to the cylinder. As the sheet that is to be fed is gripped at the front edge of the sheets which are to abut against the guides,

there is no difficulty in obtaining printing that truly registers.

The invention described differs from known cylinder printing presses with automatic sheet feeders, in that in such machines the paper pile is situated inside the machine, so that the pile greatly hinders the accessibility to the machine, to the form, and to the inking parts.

It differs also from known automatic platen presses in which the lever swings in a circle and in which the piles have been arranged outside the machine, in that in such known machines the piles are in the way and hinder accessibility to the press.

It differs also from known presses in that it is much more accurate, and in the known presses the inaccurate feeding of the sheets to the guides causes poor registration. The reason for that is that the swinging levers in the known devices grip the side edge of the sheet instead of, as in this invention, its front edge. This front edge has to be carried to the guides; therefore, if the guiding is to be correct it should also be gripped at the front by the swinging lever. For such reason, the printing, if the registering is to be true, meets considerable difficulties in the known arrangements.

In the present invention these difficulties heretofore noted are eliminated fundamentally. Both paper piles for feeding and deliver are arranged outside the machine, and the topmost sheet to be printed on is taken from the paper pile by means of a swinging lever which grips that edge of the sheet which is most advanced to the guides of the printing cylinder. The improvement described secures the handiest possible service at the press, and the sheet is advanced to the guides of the press with the greatest accuracy. The swinging lever, after its turn, that is, at the end of its motion, stands parallel to the guides, and the sheet is carried directly against the guides or on carriers that run in their own direction of movement, that is, in the direction of the turning of the press cylinder.

The delivery of the printed sheet takes place like the feeding, by means of a swinging lever which runs on the same or a separate axle from the one which is used for the feeding. As the pile of delivered sheets also is arranged outside the machine, it does not impede in any way the comfortable service at the press.

The upper cylinder cooperates with the coating cylinder in the known manner of high speed cylinder presses for sheet printing; and the feed arm enters one bite of such cylinders, whereas the delivery arm enters the other bite of said cylinders. When the paper has been fed to the entrance bite, the cylinders grip the paper and print the same, while the paper moves between the cylinders. The delivery arm in each case is so arranged that the edge of the paper, which during feeding was the front edge, is now gripped by the delivery arm. Suitable grippers, mechanical or pneumatic, well-known in the art and therefore not shown, are applied to the feed and delivery arms to engage the paper sheet for feeding and delivery.

It is obvious that various changes and modifications may be made in the details of construction and design of the above specifically described embodiments of this invention without departing from the spirit thereof, such changes

and modifications being restricted only by the scope of the following claims.

What is claimed is:

1. In a fast running printing press for sheet printing, having a cylinder and having guides, and having stacks of paper disposed outside of the press and away from the cylinder thereof, one of paper to be printed and one of printed paper, the combination of a swinging lever adapted to grip the top sheet of the stack of unprinted paper at the front edge of the sheet and deliver it to the entrance side of the cylinder prior to its printing, a second lever adapted to grip the same front edge of the sheet after it has been printed and deliver it in the same general direction of movement from the exit side of the cylinder to the stack of printed paper, the levers being so disposed in respect to each other that during the printing of the sheet free from both levers, the first lever moves in reverse direction to take up a new sheet from the unprinted stack, while the second lever moves in reverse direction to its position to grip the printed sheet after its printing, said stacks being arranged on different sides of the printing press away from the cylinder in a manner not to obstruct the same, and means for moving each of said levers to and from its respective side, whereby as the sheet is being delivered from the exit side of the cylinder, the next sheet is being fed to its entrance side.

2. A fast running printing press for sheet printing, having a cylinder and having guides, comprising stacks of paper disposed outside of the press and away from the cylinder thereof, a plurality of swinging levers arranged at right angles to each other, one adapted to grip the top sheet of one stack of paper at the front edge of the sheet and deliver it to the entrance side of the cylinder, and the other lever adapted to engage the front edge of the printed sheet and move it from the exit side of the cylinder to the other stack, said stacks being arranged on different sides of the printing press away from the cylinder in a manner not to obstruct the same, and means for moving each of said levers to and from its respective side, whereby as the sheet is being delivered from the exit side of the cylinder, the next sheet is being fed to its entrance side.

3. A fast running cylinder printing press for sheet printing, having a cylinder and having guides, comprising a swinging lever, means for swinging the lever around for about 90° to feed a sheet of paper from a stack to the entrance side of the printing cylinder, means on the swinging lever to grip the top-most sheet of the stack at the front edge of the sheet fronting the guides, means supporting the stack outside of the press away from the cylinder, a second lever to deliver the printed sheet from the exit side of the printing cylinder, means on the second lever for gripping the front edge of a sheet after it has been printed, means for delivering on the delivery stack outside of the press away from the cylinder the printed sheet after release from the second lever, means connecting the first and second levers, at 90° to each other, and means for moving said levers, whereby as the sheet is being delivered from the exit side of the cylinder, the next sheet is being fed to its entrance side.

WALTHER RÖSSGER.
